UNITED STATES PATENT OFFICE.

ALFRED BREDENBERG, OF CHAMPLAIN, NEW YORK, ASSIGNOR OF ONE-HALF TO THE SHERIDAN IRON WORKS, A CORPORATION OF NEW YORK, AND ONE-HALF TO T. W. & C. B. SHERIDAN COMPANY, A CORPORATION OF NEW YORK.

SIGNATURE-GATHERING MACHINE.

1,177,600.

Specification of Letters Patent.

Patented Apr. 4, 1916.

Application filed April 28, 1911. Serial No. 623,872.

To all whom it may concern:

Be it known that I, ALFRED BREDENBERG, a citizen of the United States, and a resident of Champlain, Clinton county, New York, 5 have invented certain new and useful Improvements in Signature-Gathering Machines, of which the following is a specification.

The present invention relates to gathering 10 machines such as are used for assembling the component parts of books or like objects, and more particularly to that class of gathering machines used in the manufacture of books wherein a series of so-called "boxes" 15 is employed, serving as containers of signatures or like book-components, from which series of containers signatures are "gathered", one signature of each sort being extracted from its container and all grouped 20 together preparatory to subsequent binding or other operations.

The invention has for an object generally 25 to improve, condense, simplify and thereby cheapen gathering machines of the class referred to, and render them easier to maintain and operate; and other and more specific objects will appear hereinafter in the following description, or will be obvious 30 therefrom.

The invention consists in the novel arrangements and inter-relations of the various instrumentalities, and in the novel combinations, constructions, mechanisms and parts hereinafter shown or described.

The accompanying drawings referred to 35 in the following description and forming a part hereof, illustrate one embodiment of the present invention, the same serving in connection with the description to explain 40 the principles of the invention.

In the drawings, Figure 1 is a side elevation 45 of a gathering machine constituting one form of embodiment of the invention. Fig. 2 is a cross-section thereof taken on the plane 2—2 of Fig. 1. Figs. 3 and 4 constitute enlarged elevations of certain details 50 from the same viewpoint as Fig. 2. Fig. 5 is a partial plan view showing generally the arrangement of the shafts X, X', X² and their interconnections. Fig. 6 is a general plan view of the gathering machine shown 55 in the other figures.

These improvements as illustrated in said

drawings comprise a novel arrangement and inter-relation of the various instrumentalities composing such a machine, and a revision and reconstruction thereof to permit such re-arranging and carry out the objects of the invention. 55

According to one feature of the present 60 invention is contemplated a particular arrangement of the consecutive series of boxes or containers which contain the supplies of signatures or the like, whereby they are located to overlap one another, for example 65 by being set in two or more overlapping rows; and a construction of the extracting and gathering instrumentalities on novel principles to accord with such arrangement of the signature boxes. 70

The above and other features of the invention will be more particularly set forth in the following description.

It will be understood that while a pamphlet, magazine or other book is usually assembled or made up from a plurality of ordinary signatures, each constituted for example of eight leaves which have been printed on one sheet of paper and folded into a signature, nevertheless, the book might be 80 made up of a group of single sheets or leaves; consequently the word "signature" shall be employed hereinafter in a representative sense as including any sort of component part of a book or analogous object. 85

The successive or consecutive signatures which have to be grouped together to make the complete book are in accordance with the present invention contained in a series of boxes so-called, and are gathered therefrom 90 one from each of the consecutive boxes and grouped together to make the complete book. In some cases there may be as many as twenty or more of these boxes or containers. There is in the drawings hereof, however, 95 shown for convenience a smaller number of boxes or containers A', A², A³, etc. These containers may take any convenient form or design so long as they suffice to contain or hold the stacks of signatures and permit one 100 at a time thereof to be removed in the gathering process. Each container may have bottom and side walls as shown, while being open at the top and rear to permit the containers to be refilled as often as necessary 105 with new supplies of signatures. What may

be termed the forward end of each container is provided with a wall or member a against which all of the signatures are to be uniformly adjusted.

- 5 According to the present invention, in distinction to arranging the series of containers in a single extended row, thus occupying very large space and requiring an unwieldy and costly machine, they are arranged 10 in what may be designated overlapping positions, by which is to be understood any arrangement in which there is a successive overlapping of the containers with consequent economy of space, etc. Overlapping 15 in accordance herewith may be overlapping in various senses. For example as illustrated, each alternate container may overlap the preceding and succeeding ones, or different arrangements may be made. As 20 shown the first container overlaps the second, the second is overlapped by the first and third, the third overlaps the second and fourth, and so on throughout the series. The illustrated arrangement may be more 25 specifically expressed by stating that the consecutive containers are arranged alternately in two or more, in this instance two, rows, levels or tiers, and it is preferred that the containers in the respective rows shall 30 be staggered or overlapped in the manner shown.

In the cross-sectional view of Fig. 2 one of the lower row of containers A' is seen and one of the upper row A^2 , each of which 35 is of such construction and location as to coöperate with means for extracting signatures and transferring them to the place where the signatures are gathered and the books assembled. Each container's bottom 40 is cut away in front for egress of a signature. To facilitate coöperation between the containers and the specific extracting means hereinafter to be described, the upper row of containers A^2 may be both set forwardly 45 and inclined forwardly as shown, whereas the lower row A' may lie flat.

The piles of signatures are designated by Y and the foremost signature or the one which is about to be transferred, by y , while Z designates the groups of accumulating signatures or the books in the process of assemblage.

To facilitate the extracting operation 55 pneumatic or other devices a' may be employed in association with each of the containers for the purpose of outwardly deflecting the forward edge of the signature y , thereby enabling it better to be gripped and removed. The device a' is shown as 60 pivoted and it may be connected with an exhausting means or otherwise caused to adhere to the face of the foremost signature for deflecting it. The device will be swung about its pivot through any convenient operating means. As shown the devices a' for

the lower row of containers are each connected by a rod a^2 with one of a number of arms a^{12} fixed on a rock shaft a^8 , one of the arms a^{12} being provided with a roller a^6 which bears on a cam a^5 , being held in constant contact therewith by a spring a^{11} extended between a fixed part of the machine and an arm a^{10} fixed on the shaft a^8 . The devices a' for the upper row of containers are each connected by rods a^3 and arms a^{13} to a rock shaft a^{14} which in turn is connected by an arm a^{15} and rod a^4 with an arm a^9 (see Figs. 1 and 5), which has a stud or roller bearing on a cam a^7 similar to the cam a^5 but oppositely disposed so that the 70 pneumatic devices a' for the respective rows of containers will be operated in alternation.

The cams a^5 and a^7 are mounted on a shaft X^2 and indirectly driven from a main shaft X which may be driven from any suitable 85 source of power. The connections may be for convenience as follows: A spur gear x is shown on shaft X and said gear x is in engagement with a second gear x' which is mounted upon a shaft X' , said last mentioned shaft having another gear X^{11} thereon which engages in its turn gear x^2 mounted upon the shaft X^2 first mentioned. The 90 bearings for the several shafts may be as shown and need not be particularly described, some of them being contained in the frame partition or wall g . The shaft X may be considered as a single mechanical part or member taking the form of a shaft 95 which has connections to the several instrumentalities comprised in the present machine for operating all of them in harmony 100 with each other, as hereinafter to be described.

The cams a^5 and a^7 on the shaft X^2 are 105 so designed and timed that each pneumatic device a' will displace the edge of the signature y just prior to the gripping of such signature by the corresponding extractor, as explained below.

Before describing the extractors C' , C^2 , etc., and their mode of actuation, reference will be made to the device which receives the extracted signatures and carries them until a complete set of signatures has been 115 gathered into a group. Such carrier is a well known instrumentality and need not be described in detail further than as follows: The carrier B may generally be stationary, preferably comprising an inclined 120 plate b having a base flange b' and a continuous slot through which project a series of traveling members or pins b^2 , these being spaced apart a proper distance to receive the assembling books between them and 125 serving to push the assembling books along the carrier while signature after signature is being added to each of the assembling books until at the end of the carrier the complete group of signatures is delivered 130

therefrom to a delivery support B' or directly or indirectly to any convenient receptacle or mechanism, such for example as a clamp for holding the signatures during the subsequent operations of binding, etc. 5 The pins b² may be secured to a sprocket chain b³ carried on two or more sprocket wheels b⁴, one of which is shown, the latter carried by a shaft whereon is a second 10 sprocket wheel b⁵ engaged by a chain with a third sprocket wheel b⁶ carried on a horizontal shaft suitably mounted in fixed bearings and having at its end a bevel gear wheel b⁷ engaging a similar gear wheel b⁸ mounted on the shaft X. 15 The extractors C', C², etc., are all substantially alike in their detail construction, but they are differently arranged and are operated at different points of time, although all are shown as having support in an overhanging frame part G. The preferred arrangement of the extractors is that certain of them, C', C³, etc., pertaining to the lower row of containers, shall be mounted on one shaft or actuating mechanism, while others of them C², C⁴, etc., shall be mounted on another shaft. It is also preferred that the first mentioned extractors shall be actuated in rotation, that is to say, 20 in this instance, in alternation, with the last mentioned ones. This is of great importance in connection with the described novel arrangement of containers. The details of the extractors will now be described, 25 and mechanism whereby the extractor series C', C³, etc., are caused to extract signatures and transfer them to the carrier at a time when the series C², C⁴, etc., are not doing this, and whereby such operation of the 30 first mentioned extractors is succeeded by a similar extracting operation of others of them. 35 One of the extractors, C', is seen in enlarged view in Figs. 3 and 4, and as shown 40 comprises a pair of grippers c, c' adapted to be opened and closed and to grip and release the signature y at the proper times. The upper gripper c may for convenience be secured to a longitudinal member in the 45 form of a tube c². Sliding within the tube c² is a rod c³ and this passes downwardly through the gripper c to where it is attached to the gripper c', the rod c³ constituting the 50 means of moving the lower gripper relatively to the other for opening and closing the grippers. A shaft c⁴ is common to, and has hung from it, all of the extractors C², C⁴, etc., while a similar shaft c⁵ is common to the extractors C', C³, etc., and each of 55 the shafts has a series of sleeves or collars c⁶, on each of which is an extension c⁷ whose cylindrical interior receives the longitudinal tube c², the two being rigidly secured together. Support is thus afforded to the 60 extractor C² by its being hung in the manner 65

described from the shaft c⁴, while the movable rod c³ passes upwardly in the interior to where at its upper end it is adapted to be actuated in a manner hereinafter to be described. 70 Referring now to Fig. 2, the shafts c⁴ and c⁵ are shown as geared to each other through a gear wheel d on shaft c⁴, and gear wheel d' on shaft c⁵, the two gears directly engaging so that whenever one shaft and the extractors thereon are swung in one direction, the other shaft with its extractors is swung reversely. The extractors C', C³, etc., will therefore be swinging downwardly while the extractors C², C⁴, etc., are swinging upwardly to obtain new signatures from the containers. 75 To cause the actuation of the extractors, an arm d² may be secured on shaft c⁵ and connected to a rod d³ which extends from the arm to a crank pin d⁴ formed on the gear wheel x² already referred to, carried on the shaft X². By this described means the revolution of the crank pin acting through rod d³ and arm d² effects the reverse oscillations 80 of the shafts c⁴, c⁵ carrying the extractors, the throw of the crank pin being sufficient to carry the extractors from one extreme position to the other, such extreme positions being as seen in Fig. 2. As will hereinafter 85 appear each extractor while in upward position will be operated to grip a signature, and while in its lower position will be operated to release and eject the signature. 90 For opening and closing the grippers c, c', 100 the following is a convenient mechanism: A collar c⁸ on the movable rod c³ of the gripper c' is pressed upward by spring c⁹ tending to close the grippers, while the upper end of the rod c³ is designed to be depressed for 105 opening the grippers. For this purpose special cams E', E² are employed, the former for the extractors C', C³, etc., and the latter for the extractors C², etc. Each of these cams E' is pivotally mounted between extensions e of the casting c⁷, and comprises besides the cam portion a toe extension e' projecting through a slot formed at e² in one side of the casting c⁷. The toe e' bears directly upon the top of the rod c³. The cam E' is swung about its pivot by a roller e³ mounted on an arm e⁴, while the cam E² is similarly operated by a roller e⁵ on an arm e⁶, the two arms e⁴, e⁶, shown as being mounted through sleeves or collars upon an oscillating shaft e⁷. Any rocking of such shaft will be transmitted to both the rollers e³, e⁵ so as to simultaneously actuate both of the cams E', E², but each cam will be operated in a manner opposite to the other so that the several grippers of the extractors C', C³, etc., will be opened while the grippers of the other extractors will be closed, and vice versa. To oscillate the shaft e⁷ to carry out 110 these purposes, said shaft is provided with 115 120 125 130

an arm e^8 extending therefrom and pivotally connected to a rod e^9 , which extends from the arm e^8 to the roller e^{10} guided in its up and down movements by an arm e^{11} loosely mounted on the same shaft X' that carries gear x' , said shaft for convenience passing through wall g for this purpose. Said roller e^{10} engages in a cam groove e^{12} formed in the side face of a cam e^{13} mounted on the same shaft X^2 that carries the gear x^2 previously referred to. The cam groove e^{12} is of a contour having opposite eccentric portions for actuating the rod e^9 and thereby opening or closing the grippers of the respective extractors, and two opposite concentric portions permitting the grippers to remain substantially open or closed during the swinging movements of the extractors.

The above substantially completes the description of the mechanism with the exception of an ejecting device F that is preferably employed, one of which may be mounted on each extractor, and each of which may consist in an arm f extending from a pivot f' downwardly to a position adjacent the grippers c, c' , said arm being designed to be thrown forwardly at the proper time to eject a signature from the grippers so as to insure the proper deposit of the signature upon the carrier B . To operate such an ejector it may have a second arm f^2 having a pin or roller f^3 coöperating with a fixed cam f^4 so located that said cam forces the pin downwardly just as the extractor reaches its lowest position so as to sharply throw the arm f of the ejector to strike the signature held between the grippers. A spring f^5 may be employed tending to return the ejector to inactive position.

The preferred operation of the above described parts will be as follows, assuming the carrier to be in operation and the several signature containers to be supplied with signatures. The extractors of the first series will approach the lower tier of containers, and the gripper jaws of each extractor will pass one on each side of the foremost or lowest signature, the latter having been bent or curved slightly downward by the pneumatic device a' . At this stage the cam e^{13} will operate to cause the gripper jaws to close upon the signature, which is thus firmly gripped. Fig. 2 shows extractor C' in this position. In the meantime the crank pin d^4 , which has brought the first series of extractors to upper position and momentarily held them there, passes by the center and commences to withdraw or lower the extractors, each gripping a signature, the extractors finally arriving at lower or delivering position as seen at C^2 , Fig. 2; in the meantime all of the second series of extractors for the other tier of containers having been moving upwardly for the purpose of in their turn

securing signatures from their containers to be transferred to the carrier. On reaching lowest position each extractor releases the signature by reason of an eccentric portion of the cam e^{12} coming into play to open the grippers, and thereupon the ejector operates through the contact of its pin f^3 with the cam f^4 . After the signature is thus delivered to the carrier the extractors C', C^3, C^5 return upwardly, while the other extractors in their turn carry signatures downwardly to the carrier. During all of this operation the carrier B will be operated, or rather the pins b^2 thereof will be actuated, at a certain speed of movement or in other manner to accord with the other operations. The pins do not travel the entire width of a container for each extractor operation, but on the contrary move only a fraction of such width, in this case substantially a half thereof. To put it more accurately the carrier pins travel, during the time between the operations of two succeeding extractors, a distance equal to the horizontal distance between the centers of two consecutive containers, which may be termed the "container spacing" and is preferably uniform throughout the entire series A', A^2, A^3 , etc. Forward of each of the pins b^2 a book is being assembled and as the pin moves along it receives at the front of it, first, a signature from box A' . Thereafter on moving the short distance or "container spacing", from the box A' to the box A^2 , a signature from box A^2 is deposited forward of the pin b^2 and directly on top of the preceding signature. A further sliding movement of the pin b^2 carries it in position below the third box A^3 and thereupon is received a signature therefrom, this operation continuing throughout the machine, or throughout as many boxes as there are signatures to be comprised in a book, until the latter is completely assembled. It is not important that the pins b^2 of the carrier should travel continuously but their average speed is important, so that each pin will be brought consecutively opposite the respective boxes as the extractors are removing signatures therefrom and delivering them to the carrier; and the sprocket and bevel gear wheels referred to will be so proportioned as to secure the correct speed to attain this end. Needless to say there are a continuous series of pins b^2 in front of each of which the signatures to be formed into a book are assembled so that the machine continuously delivers completely assembled books ready for binding.

It was above stated that the successive complete groups of signatures upon delivery from the gathering devices may be transferred directly or indirectly to a clamp for holding the signatures during the subsequent operations of binding. Traveling

clamps of this nature, is should be stated, are shown in the bookbinding machine of my prior Patent No. 1,073,324, dated September 16, 1913, wherein the trimming and 5 gluing or other binding operations are performed on each book as the clamp in which it is held progresses from mechanism to mechanism; while the above mentioned scheme of providing mechanism for transferring the progressing complete signature 10 groups, after they successively issue from the gathering machine hereof into such binding machine clamps, is shown and claimed in my prior Patent No. 1,051,074, dated January 21, 1913.

It will be seen that by reason of the construction above shown and described, a gathering machine is provided which answers the objects and affords the advantages of 20 the invention as hereinbefore set forth; and other advantages will be apparent to those skilled in the art.

It is to be understood that the invention in its broader aspects is not limited to the 25 precise construction shown nor to any particular construction by which the invention has been or may be carried into effect, since many changes may be made in the details of the parts without departing from the 30 main principles of the invention and without sacrificing its chief advantages.

What I claim and desire to secure by Letters Patent is:

1. A signature gatherer including in combination a plurality of signature containers arranged in two equally spaced sets in staggered relation, two sets of extractors therefor, means for reciprocating the extractors alternately in sets so that the extractors of 35 one set operate while those of the other set are inoperative, a support onto which the extracted signatures are placed by the extractors, and means for feeding the signatures along the support an amount equal 40 to half the distance between the centers of adjacent containers in one set in a period equal to the time from one extracting operation to the next.

2. A signature gatherer including in combination a plurality of signature containers from which signatures are to be taken in 50 succession to be grouped and bound into a book, said containers arranged so that each container is lapped by the succeeding one 55 and so that the spacing between successive container centers is less than the length of a container, movable extractors for extracting signatures from said containers, mechanism for actuating the extractors so that in 60 each extracting operation signatures are extracted from a fraction only of the containers, in the next operation from a similar fraction and so on, and means for feeding 65 forwardly a procession of the gathering signature-groups by an amount substantially

equal to the between-center spacing of consecutive containers in the period from one extracting operation to the next.

3. A signature gatherer including in combination a plurality of signature containers 70 from which signatures are to be taken in succession to be grouped and bound into a book, said containers arranged in a plurality of sets in staggered relation, so that successive containers are spaced between 75 centers a distance less than the length of a single container, movable extractors for extracting signatures from said containers, mechanism for actuating the extractors so that in each extracting operation signatures 80 are extracted from one set only of the containers, in the next operation from another set and so on, and means for feeding forwardly a procession of gathering signature-groups by an amount substantially equal to 85 the between-center spacing of consecutive containers in the period from one extracting operation to the next.

4. A signature gatherer including in combination a plurality of signature containers 90 from which signatures are to be taken in succession to be grouped and bound into a book, said containers arranged in a plurality of sets in staggered relation, so that successive containers are spaced between centers a distance less than the length of a single container, movable extractors for extracting signatures from said containers, there being 95 a set of extractors for each set of containers, mechanism for actuating successively the sets of extractors, and means for feeding forwardly a procession of gathering signature-groups by an amount substantially equal to the between-center spacing of consecutive containers in the period 100 from one extracting operation to the next.

5. A signature gatherer including in combination a plurality of signature containers from which signatures are to be taken in 110 succession to be grouped and bound into a book, said containers arranged in a plurality of sets in staggered relation, so that successive containers are spaced between centers a distance less than the length of a single container, movable extractors for extracting signatures from said containers, there being 115 a set of extractors for each set of containers, mechanism for actuating successively the sets of extractors, and means for feeding forwardly a procession of gathering signature-groups by an amount substantially equal to the between-center spacing of consecutive containers in the period from one extracting operation to the next; said extractors having movable jaws, and mechanism for automatically opening and closing 120 said jaws in harmony with the extractor movements.

6. A signature gatherer including in combination a plurality of signature containers 125

arranged in two equally spaced tiers in staggered relation, two sets of swinging extractors therefor, means for actuating the extractors alternately in sets so that the extractors of one set operate while those of the other set are inoperative, said actuating means comprising an oscillating shaft carrying the extractors for the upper tier of containers and another oscillating shaft carrying those for the lower tier and mechanism for alternately oscillating said shafts, and means for feeding the gathering signatures forwardly an amount equal to half the distance between the centers of adjacent containers in one set in a period equal to the time from one extracting operation to the next.

7. A signature gatherer including in combination a plurality of signature containers from which signatures are to be taken in succession to be grouped and bound into a book, said containers arranged in a plurality of horizontal tiers in staggered relation, so that successive containers are spaced between

centers a distance less than the length of a single container, a set of movable extractors for each tier of containers, mechanism for actuating successively the sets of extractors and feeding means for horizontally advancing a continuous procession of gathering signature-groups, said feeding means adapted to advance each signature-group by an amount substantially equal to the between-center spacing of consecutive containers in the period from one extracting operation to the next, whereby as the signature-group travels by the container series, it is supplied with signatures from the consecutive containers and attains its full complement of signatures at the end of its horizontal travel.

In testimony whereof, I have signed my name to this specification, in the presence of two subscribing witnesses.

ALFRED BREDENBERG.
